United States Patent Office

Des. 185,246
Patented May 19, 1959

185,246

MASSAGER

George Dan Taran, Honolulu, Territory of Hawaii

Application January 12, 1959, Serial No. 54,151

Term of patent 14 years

(Cl. D83—1)

Fig. 1 is a perspective view of a massager showing my new design;

Fig. 2 is a reduced-size bottom plan view; and

Fig. 3 is a front end elevational view.

I claim:

The ornamental design for a massager, substantially as shown.
